INTERCHANGEABLE BALANCE STAFF FOR WATCHES

Jacob Hazai Beckmann, New York, N. Y.

Application February 15, 1940, Serial No. 319,005

1 Claim. (Cl. 58—140)

This invention relates to new and useful improvements in a balance staff for watches.

Heretofore balance wheels of watches were constructed with staffs which are a drive fit, and which were hard to remove when it was necessary to repair the movement of the watch. After the repair work was completed and it was again desired to place the balance wheel on the balance staff, it was necessary to hammer upon the staff in order to fixedly attach the wheel thereto. After the watch had been repaired a number of times the hammering pounded down and compressed portions of the wheel body resulting in a loose fit between these parts which permitted the wheel to slide on the staff.

More specifically, this invention proposes the construction of a slide fit for the staff of balance wheels which may be repaired any number of times without destroying the operative value of these parts.

Still further the invention proposes the use of a staff having a cylindrical support portion which may be engaged into the axial opening of a balance wheel and also having a head portion engaging against a portion of said wheel body, and staff elements extending axially from the opposite ends of said portions for rotatively supporting the staff within the watch body.

As another object of this invention it is proposed to construct a novel type of spring hub cap which may be threadedly engaged on the staff element on the opposite side to the head portion of said staff and clamping this cap against the wheel to fixedly engage the balance wheel on the staff body, so as not to interfere with the fittings and positioning of the usual hair spring of the watch.

As another object of the invention it is proposed to construct the cylindrical support portion and the head portion of the staff of separate sections and applying a means thereto for holding the separate sections in different relative positions to compensate for the compressed wall areas which will be formed on the balance wheel body as the result of repairing.

Still further the invention proposes the use of opposed overhanging flanges formed on the separate sections of the cylindrical support portion and the head portion which may have shims engaged therebetween to separate these sections and compensate for the compressed wall areas.

For further comprehension of the invention, and of the objects and advantages thereof, reference will be had to the following description and accompanying drawing, and to the appended

claim in which the various novel features of the invention are more particularly set forth.

In the accompanying drawing forming a material part of this disclosure:

5 Fig. 1 is a plan view of a balance wheel having a staff, constructed according to this invention.

Fig. 2 is an enlarged sectional view taken on the line 2—2 of Fig. 1.

10 Fig. 3 is a cross section of the hub cap per se.

Fig. 4 is an enlarged detailed view of a portion of Fig. 2.

Fig. 5 is a view similar to Fig. 4 but illustrating a modification of the invention.

Fig. 6 is a plan view of Fig. 5.

15 Fig. 7 is another view similar to Fig. 4 but illustrating a still further modification of the invention.

Fig. 8 is a view similar to Fig. 4 but illustrating another modification of the invention.

20 Fig. 9 is a perspective view of the tool which is to be used for engaging the spring hub cap on the staff.

The balance staff for watches, according to this invention, comprises a balance wheel body 10 having an axial opening 11 for a staff 12. This staff 12 has a cylindrical support portion 12^a engaging into the axial opening 11 and a head portion 12^b engaging against a portion of said wheel body on one end of said opening. Trunnion elements 12^c extend axially from the opposite ends of the support portion 12^a and the head portion 12^b.

25 Fig. 10 is a perspective view of the tool which is to be used for engaging the spring hub cap on the staff.

30 A hub cap 13 is threadedly engaged on the trunnion element 12^c which is opposite the head portion 12^b and may be clamped against a portion of said wheel body 10 for releasably holding the wheel 10 fixed upon the staff 12.

The balance wheel body 10 consists of a rim portion 10^a having a plurality of openings 10^b into which balance pins 14 are threadedly engaged to make the wheel operate properly on the staff 12.

35 Spokes 10^c radiate from the inside wall of the rim 10^a and converge on a common center which is provided with said axial opening 11. The staff 12 is constructed of steel, while the balance wheel is constructed of brass which is a softer material than steel. For this reason the cylindrical support portion 12^a of the staff 12 engages into the axial opening 11 to support the walls of this opening to prevent them from being

40 pressed out of shape when the hub cap 13 is clamped thereon to fixedly attach the balance wheel 10 to the staff 12.

45 The hub cap 13 engages into an enlarged recessed portion 11^a of the axial opening 11 and has its bottom edge engaged against the shoul-

50 ders of the staff 12.

der portions 11^b formed by this enlarged recess for fixedly clamping the spokes 10^c between the bottom edge of the hub cap 13 and the top edge of the head portion 12^b . This hub cap has a threaded opening 13^a which cooperates with complementary threads 12^d formed on the trunnion elements 12^c for clamping the balance wheel upon the staff. The flange 13^c of hub cap 13 is further provided with radial slots 13^b into which a specially constructed tool 15 may be engaged for turning the cap 13 on and off the threaded trunnion element 12^c . This specially constructed tool 15 comprises a strip of material 15^a having beveled portions 15^b formed on one of its ends which may be engaged into the slots 13^b formed in the hub cap 13 . The hub cap has a dome-shaped portion and therefore the end of the strip of material 15^a which is provided with the beveled edge 15^b also has a dome-shaped cutout 15^c intermediate of the edges of the strip of material which conforms with the dome on the hub cap permitting it to be engaged over the top of this cap and into the slots 13^b for turning the cap.

The tool 15 is provided with a handle portion 15^d in which a rotary stem $15'$ is held. This stem is formed with a head portion 15^e at one end for rotating the flat portion 15^a at the other end of stem $15'$. A hair spring 16 is adapted to have one of its ends securely attached in any desired way to the hub cap 13 for fixedly attaching it to the staff 12 . This hair spring 16 is of a construction which is generally used in connection with balance wheels of this type and neither spring nor its manner of attachment forms any part of this invention.

In Figs. 5 and 6, the flange 13^c of the hub cap 13 is fully embedded into a recess 10^d formed at the mid-portion of spoke 10^c by bending the spoke downwardly into a U-shape 10^f . In this form of the invention the top surface of flange 13^c is flush with the top surface 10^e of the spoke 10^c , so as to permit the hair spring 16 to be connected close to the spoke surface 10^e .

According to the modification of the invention shown in Fig. 7 a means is provided for holding relative portions of the staff 12 for withdrawing portions of the cylindrical support portion to different amounts to compensate for the compressed wall areas and repair clamping action of the hub cap.

This means comprises a staff $12'$ having a cylindrical support portion 12^a integrally formed therewith and adapted to engage into an axial opening 11 formed in the spokes 10^c of a balance wheel 10 . This cylindrical support portion has an outward extending flange 12^e on its bottom edge which engages the inner face of a separate head portion $12''$ which is formed with an inwardly directed flange 12^f which engages the outer face of the cylindrical support portion 12^a and against the bottom face of the spoke 10^c in the vicinity of the axial opening 11 . A hub cap 13 is provided with a threaded opening 13^a which may be threadedly engaged upon the trunnion element 12^c which is opposite the head portion $12''$ for clamping the balance wheel on the head portion $12''$.

When it is seen that a portion of the spokes 10^c in the vicinity of the axial opening 11 is becoming compressed from the clamping action of the hub cap 13 permitting the adjacent faces of the hub cap and the cylindrical support portion to

contact each other forming a loose fit between the hub cap 13 and the head portion $12''$, it is possible to form an adjustment between the cylindrical support portion 12^a and the head portion $12''$ to withdraw a portion of the cylindrical support portion 12^a from the axial opening 11 to compensate for the compressed wall portions.

This adjustment may be formed by engaging shims 17 between the opposed overhanging flanges 12^e and 12^f of the cylindrical support portion 12^a and the head portion $12''$ respectively. When these shims are engaged between the opposed flanges it increases the space between these flanges causing the cylindrical support portion 12^a to be slightly withdrawn from the axial opening 11 to keep it out of contact with the hub cap 13 to permit this hub cap to properly clamp the balance wheel 10 upon the head portion $12''$ of the staff $12'$. In other respects this form of the invention is the same as that shown in the previous figures, and corresponding parts may be recognized by the same reference numerals.

Furthermore, a staff constructed in accordance with this latter modification of the invention may be used in connection with a balance wheel 10 , having spokes 10^c of any desired thickness. If the spokes are constructed of relatively thick material, fewer shims 17 will be needed to keep the cylindrical support portion 12^a from contacting the hub cap 13 . On the other hand, if the spokes 10^c are of thinner material, it will be required that more shims 17 be engaged between the flanges 12^e and 12^f , for withdrawing the greater portion of the cylindrical portion 12^a from the axial opening 11 , and so keep this cylindrical support portion 12^a from contacting the hub cap 13 .

In Fig. 8, the hub cap 23 is made integral with spoke 20 and staff 22 is screwed into the threaded opening 23^a of the hub cap. The head portion 22^b of the staff is provided with radial slots 21 for screwing the staff into the threaded hub cap.

It is to be understood that this device may be made in various sizes to accommodate different sizes of watches, also that the arrangement may be fitted on present old watches or on any new manufactured watch.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

In a watch balance staff having a balance wheel body with an axial opening therethrough, a staff extending through said opening, said staff having an outwardly extending flange on one side of said wheel body, a hub cap on the other side of said wheel body engaging said other side of said body, a sleeve member encircling said outwardly extending flange and having an inwardly extending flange engaged between said outwardly directed flange and said one side of said wheel body, and shims mounted between said flanges and within said sleeve member.

JACOB HAZAI BECKMANN.
